UNITED STATES PATENT OFFICE.

EDWARD C. HOYER, OF CINCINNATI, OHIO, AND EDWARD C. HOYER, JR., OF RICHMOND, VIRGINIA.

COMBINATION ADJUSTABLE SCHOOL DESK AND CHAIR.

1,369,108.

Specification of Letters Patent. Patented Feb. 22, 1921.

Application filed March 24, 1920. Serial No. 368,363.

To all whom it may concern:

Be it known that we, EDWARD C. HOYER and EDWARD C. HOYER, Jr., citizens of the United States, residing at Cincinnati and 5 Richmond, respectively, in the counties of Hamilton and Henrico and States of Ohio and Virginia, respectively, have invented certain new and useful Improvements in Combination Adjustable School Desks and 10 Chairs, of which the following is a specification, reference being had to the accompanying drawings.

This invention relates to an improved combined adjustable school desk and chair, 15 and an object of the invention is to provide a single standard provided with like means at opposite portions, for adjustably supporting a chair seat and a desk, the seat being in advance of the desk, so that when 20 units of this kind are placed in rows in the school room, the seat in advance of one desk will be used by the pupil sitting at the desk at the rear of the standard in advance.

25 The invention further aims to provide a single supporting standard for a chair and desk, and mounting said parts on the standard in very close relative positions, so that in placing these units in rows, it is possible to economize on the space consumed.

To accomplish this result it is not only the aim to adjust the chair seat and its back and the desk vertically, but it is also the aim to mount the back of the chair seat 35 so that it may swing in a vertical plane relative to the seat in order to permit either the chair seat or the desk to have a partial rotary movement prior to its vertical adjustment. In other words, in adjusting 40 either the desk or the chair seat it is first necessary to impart a slight rotary movement to one or the other, and since they are designed to be so closely arranged it is necessary to provide some means, whereby 45 the back may be positioned substantially in a relative parallel plane with the chair seat in order to enable either the seat or the desk to be given the partial rotary movement.

The invention further aims to provide 50 an article of furniture of this kind for school rooms wherein the chair seat or the desk can be very readily adjusted without interfering with the other, and without having an exceedingly limited vertical move-

ment, and this has been accomplished by 55 the provision of a novel form of standard including a single brace, and forwardly and rearwardly supporting arms, so relatively disposed as to support the desk and the chair in close relative positions. 60

The invention still further aims to provide means whereby the back of the chair seat is capable of being swung in a vertical plane to a position parallel with the chair seat so as to permit either the chair seat or 65 the desk to partially turn when adjusting the same.

The invention additionally aims to provide an improved adjustable mounting for the standard of either the chair seat or the 70 desk, of such simple, efficient and practical construction as to permit it to be cheaply made and sold at a reasonable profit.

The invention also aims to use the improved mounting on a single standard, in 75 order to support a single desk or a single chair, so that a single desk may be disposed at the front end of the row and a single chair at the rear end of the row.

While the design and construction at 80 present illustrated and set forth is deemed preferable, it is obvious that as a result of a reduction of the invention to a more practical form for commercial purposes, the invention may be susceptible to changes, and 85 the right to these changes is claimed, provided they are comprehended within the scope of what is claimed.

The invention comprises further features and combination of parts, as will be herein- 90 after set forth, shown in the drawings and claimed.

In the drawings:—

Figure 1 is a view in elevation of several supported chairs and desks in order to disclose a single row of such units with a single desk at the front end and a single chair at 95 the rear end,

Fig. 2 is an enlarged elevation of a standard for supporting a chair and a desk, showing one mounting in full elevation and the other mounting in partial elevation. 100

Fig. 3 is an enlarged elevation of the mounting,

Fig. 4 is a vertical sectional view through 105 the mounting,

Fig. 5 is a cross sectional view on line 5—5 of Fig. 4,

Fig. 6 is an enlarged view in elevation of the single standard for the support of a single desk or single chair, and

Fig. 7 is a detail view of the connections between the back of the chair seat and the seat.

Referring more especially to these drawings, 1 designates a standard which may be constructed of any suitable metal preferably 10 cast metal, and which is hollow as illustrated, and has at one end a broad circular base 2 provided with suitable openings for the reception of securing means 3, whereby the standard may be secured to the floor of 15 the school room.

The standard is simple in its construction and its upper part merges into a forwardly extending horizontal arm 4 and an upwardly and rearwardly curved arm 5. Each 20 of these arms merge into a cylindrical supporting sleeve 6, the wall of which is provided with a vertical elongated slot 7. One edge of this slot is formed with a plurality of notches 8. A supporting standard or rod 9 which is preferably hollow, though not necessarily, is designed to engage the sleeve as shown in the drawings, and this standard or rod is adapted to support either a chair seat or desk. In fact 25 in the drawings there are two standards or rods 9 provided, one supporting a chair seat 10, and the other supporting a desk 11. In order to support either the chair or the desk, the end of the standard or rod 9 is provided 30 with an enlarged supporting plate 12, which is secured to the under face of the chair seat or the desk as at 13. The standard or rod 9 engages a socket of this plate, and is held therein in any suitable manner, either by 35 friction or by any other suitable means. The standard or rod 9 is provided with a transverse pin 14 which is connected to the standard after it has entered the supporting sleeve. A portion of this pin 14 40 protrudes beyond the surface of the standard or rod 9 and extends through the elongated slot 7 of the sleeve. It is to be noted that the standard or rod 9 is capable of having slight rotary movements when adjusting the 45 standard with relation to the sleeve. However, when the chair or desk is normally supported in any suitable adjusted position, the projecting part of the pin 14 is adapted to seat in the crotch of any one of the 50 notches, and owing to these notches being arranged on slight inclined planes, the projecting part of the pin 14 will be assisted in retaining itself in engagement with the notch. In order to insure holding the 55 projecting part of the pin 14 in any one of the notches, the supporting sleeve has a boss 15 provided with a threaded bore 16 extending therethrough. A screw 17 engages the threaded bore 16 and is provided with an 60 enlarged hand wheel 18 so that if the pro- 65

jecting part of the pin 14 is in engagement with the crotch of one of the notches, the screw 17 may be tightened up by manipulating the hand wheel so that the end of the screw 17 may bear against the surface of the standard or rod 9 thereby holding the projecting part of the pin 14 in engagement with the crotch of its respective notch. It is obvious that the chair seat or the desk can be readily adjusted to any desired position by simply loosening the screw 17, imparting a slight rotary movement to the standard or rod 9 to disengage the projecting part of the pin 14 from its respective notch and then by moving the chair seat or 80 the desk up or down, and imparting a slight reverse rotary movement to the chair seat or desk, the projecting part of the pin 14 may be caused to engage another of the notches. After this is done, the screw 17 85 can be again tightened, and thereby holding the desk or chair in the desired adjusted position. It might be said that the adjustment of the chair or desk will be easily accomplished by any person, either the teacher, the janitor or even the pupil, as the construction of the mounting for the standard or rod 9 is so very simple in design and operation.

It has been found that in order to economize on the space to be used by units of this kind in the school room it is necessary to construct the supporting standard 1 so as to hold the desk and the chair in very close positions. It has been found that in doing this, the chair seat or desk when imparting a rotary movement to either of them when adjusting either article, the chair back will 95 abut the desk, and vice versa. It is obvious that should the chair and the desk be 100 mounted on the supporting standard, so as to permit of sufficient freedom of movement to allow the adjustment of either article it will 105 necessitate more floor space. Therefore, in order to economize on the floor space and at 110 the same time enable the chair or desk to be partially rotated for vertical adjustment, it has been the aim in the present instance to mount the chair back 19 so that it can be 115 swung in a vertical plane, and to a horizontal position on the chair seat. It will be noted that the chair back 19 has secured upon the lower portions of the opposite side edges by means of screws 20 plates 21. These plates 120 are provided with forwardly extending ears or lugs 22, which are pivoted by means of screws 23 to the opposite side edges of the chair seat 10 in such a manner that the chair back is capable of being swung in a vertical plane and to assume an approximately 125 parallel position relative to the chair seat. In order to limit the backward movement of the chair back, when it is desired to dispose the same for use, and at the same time to 130 permit the chair back to collapse in a direc-

tion toward the seat, suitable toggle links 24 and 25 are provided. One set of links 25 have their lower ends pivotally connected to the opposite side edges of the chair seat 5 by means of the screws 26. The upper ends of the other links 24 are pivotally connected to the opposite side edges of the chair back by means of the screws 27. The links 24 and 25 are pivotally united as at 28. Adjacent 10 where the links 24 and 25 are pivotally united, they are provided with abutting shoulders 29, which prevent the links from collapsing rearwardly and downwardly, when disposing the chair back in an opera- 15 tive position.

It will be noted that when it is desired to adjust the chair or the desk or both, it is first necessary to collapse the chair back by swinging the same in a vertical plane to a 20 position substantially parallel with the chair seat. This can be done by collapsing the top of the chair back and moving it forwardly first having moved the links 24 and 25 in order that they may collapse as shown in 25 dotted lines. When the chair back is so disposed as shown in dotted lines either the chair or the desk, or both can be readily adjusted vertically. As before stated, to adjust the chair or the desk it is first necessary 30 to loosen the screw 17, then imparting a slight rotary movement to the standard or rod 9 disengaging the projecting part of the pin from its respective notch, then the standard or rod 9 can be moved vertically. The 35 pin can be returned to one of the notches, it depending on the position the chair or the desk is to assume, and then the screw 17 may be again tightened.

It will be noted that the supporting standard 1 is of such a construction and the chair and desk are so disposed with relation to each other and with relation to the standard that either one can be adjusted with freedom of movement, with respect to each other, and 45 respectively with respect to the top part of the supporting standard 1. In this way either the desk or the chair is capable of having a wide range of adjustment, which is not found to be the case in devices of similar 50 character. As shown in the drawings, it is obvious that a single mounting can be mounted on a single standard, so that a single desk or single chair may be supported. This is necessary in order to support the single desk 55 at the front end of the row of such units, and a single chair at the rear end of the row, for if it were not for the use of a single standard with a single mounting and a single school furniture unit thereon there would be 60 an idle chair and an idle desk at each end of the row. Furthermore, it is obvious that these school furniture units are supported on a single standard in the manner shown, namely the chair in advance of the desk in 65 order to provide the usual foot and leg

space between the chair and the desk in front. In other words, should a chair be supported on the same standard in the rear of the desk, so that an occupant of the chair can use the desk supported by the same standard by 70 which the chair is supported, would necessitate the pupil or the occupant of the unit to straddle the supporting standard. For example in an instance of this kind the occupant would be required to throw one leg 75 over the standard, which would not permit the unit to be used by the female pupils, with convenience. However, it is possible to arrange the chair and the desk on the same standard so that the occupant of the 80 chair can use the desk, by enlarging the base of the standard toward the rear, and permitting the supporting arm for the chair to rise from the base of the standard instead of projecting rearwardly from the base of 85 the standard as shown in Fig. 6. In this case there will be no necessity of the pupil throwing one leg over the standard, or straddling the same when in sitting posture.

The invention having been set forth, what 90 is claimed as new and useful is:—

1. In a school furniture unit, the combination with a supporting standard having forwardly and rearwardly projecting arms, each of said arms terminating in a supporting sleeve, of a furniture unit having a supporting standard engaging said sleeve, said sleeve having a vertical slot, one edge of the slot having notches and means carried by the standard which engages the sleeve to engage any one of the notches to hold the furniture unit in different adjusted positions, and a member to tighten up on the standard of the furniture unit to insure holding the furniture unit in different adjusted vertical 100 positions, one of the furniture units having a chair back, and means for mounting the chair back on the chair seat, whereby the chair back is capable of being swung vertically toward a horizontal position parallel 110 with the chair seat and below the other furniture unit, whereby either one of the furniture units may be partially rotated so that either can be adjusted vertically.

2. In a school furniture unit, the combination with a supporting standard having forward and rearwardly extending supporting arms, of a furniture unit mounted to be adjusted in a vertical plane on each of said arms, the rear arm curving upwardly and rearwardly and terminating in a plane at a substantial distance above the plane of the forward arm, the furniture unit of the forward arm having a chair back foldable to a horizontal plane below the other furniture 125 unit, whereby either one of the furniture units may have a wide range of adjustment without interference with each other, or without interfering with the standard.

3. In a school furniture unit, a support- 130

- ing standard having forwardly and rearwardly projecting arms, the former being in a plane below the latter, each of said arms terminating in a supporting sleeve, a furniture unit having a supporting standard operatively and adjustably engaging each of said sleeves, means for holding the standard of each unit in different adjusted positions in the sleeve, one of said furniture units 10 having a furniture unit element movable to a position in a plane below the other furniture unit, whereby either furniture unit may be adjusted vertically without interfering with the other.
- 15 4. In a school furniture unit, a supporting standard having forwardly and rearwardly projecting arms, the former being in a plane below the latter, a furniture unit having a supporting standard operatively

supported on the end portion of each arm, 20 means for holding the standard of each unit in different adjusted positions, one of said furniture units including furniture unit elements, one being disposed constantly in a horizontal plane below the other furniture 25 unit, the other element being operatively connected to the constant horizontally disposed element and being positioned normally vertically adjacent the other furniture unit and being movable to a position in 30 a plane below said other furniture unit whereby either furniture unit may be rotated during its vertical adjustment without interfering with the other.

In testimony whereof we hereunto affix 35 our signatures.

EDWARD C. HOYER.

EDWARD C. HOYER, JR.
